UNITED STATES PATENT OFFICE.

ELLENE A. BAILEY, OF NEW YORK, N. Y.

DESIGN FOR A BOTTLE.

SPECIFICATION forming part of Design No. 17,047, dated January 4, 1887.

Application filed September 3, 1886. Serial No. 212,646. Term of patent 3½ years.

To all whom it may concern:

Be it known that I, ELLENE A. BAILEY, of the city, county, and State of New York, have invented a new and original Design for Bottles, 5 of which the following is a full, clear, and exact description, reference being had to the accompanying drawings, making part of this specification, in which—

Figure 1 is a face view of my new design 10 for bottles. Fig. 2 is a side view of the bottle.

The leading feature of my design consists in a bottle having the shape and appearance of a whisk-broom, and a stopper on said bottle.

15 A is the bottle or body, having the shape and appearance of a whisk-broom. B is the representation of the cap or head of the broom. C is the neck of the bottle, having the appear-

ance of the handle of the broom. D is the stopper, having the appearance of the head 20 of the handle of the broom.

Having thus described my design, I claim as new and desire to secure by Letters Patent—

The design for a bottle, substantially as herein shown and described, the same consisting of the body A, the neck C, the head or cap B, and the stopper D, and having the conventional shape of a whisk-broom.

In testimony that I claim the foregoing as my invention I have signed it this 29th day 30 of May, 1886.

ELLENE A. BAILEY.
